UNITED STATES PATENT OFFICE

97,240

DESIGN FOR A RADIATOR COVER FOR AUTOMOBILES

Hyman Mover, Brookline, Mass.

Original application October 23, 1934, Serial No.
53,728. Divided and this application August
24, 1935, Serial No. 58,280

Term of patent 14 years

To all whom it may concern:

Be it known that I, Hyman Mover, a citizen of the United States, residing at 61 Babcock Street, Brookline, in the county of Norfolk and State of Massachusetts, have invented a new, original, and ornamental Design for Radiator Covers for Automobiles, of which the following is a specification, reference being had to the accompanying drawing, in which

Figure 1 shows a front elevational view of the radiator cover in a closed position and

Figure 2 shows a similar view in an open position.

This application is a division of my application Serial Number D-53,728 filed October 23, 1934 and relates in particular to Figures 3 and 4 of that application.

The present design comprises as the principal and dominating features thereof the V-shaped outline at the upper edge of the cover when open, the V-shaped garnishing strips spaced from said upper edge, and the relationship of said upper edge and garnishing strips to each other and to the extremities of the cover, whereby, in addition to the V-shaped presented by the upper edge and garnishing strips respectively in themselves, the cover as a whole presents a substantially V-shaped appearance both inwardly and outwardly of the garnishing strips when the cover is either open or closed.

I claim:

The ornamental design for a radiator cover for automobiles and shown, and described.

HYMAN MOVER.
